CARRIER FOR BOTTLES AND THE LIKE

Raymond N. Bostock, Upper Montclair, N.J., assignor to P. Ballantine & Sons, Newark, N.J., a corporation of New Jersey

Filed Feb. 24, 1954, Ser. No. 412,197

9 Claims. (Cl. 229—23)

This invention relates to carriers of the type used for transporting a plurality of containers, such as glass bottles and the like.

Open top cartons, that is cartons having bottom, side and end walls, but not a top wall or cover, have been used for a number of years for the purpose of storing and transporting various items of merchandise, including glass bottles containing beer, soft drinks or other liquids. Such cartons are usually provided with partitions that divide their interiors into compartments for receiving individual bottles to prevent the bottles from coming into direct contact with each other, thereby minimizing the possibility of breakage of the bottles in the course of handling.

Due to the weight of the merchandise and the rough handling to which loaded cartons are frequently subjected, present-day open cartons are generally constructed of heavy fibreboard. It is often necessary, in order to provide adequate strength and rigidity, to reinforce the cartons in various ways. As a consequence, such cartons are quite expensive.

Certain present-day cartons of the character indicated above are designed and capable of being reused a number of times, under normal conditions. These cartons, as well as other cartons now available, often become damaged or marred by the weather and by scuffing, and, as a consequence, are either weakened structurally or rendered so unsightly that they must be discarded after being used only a relatively few times.

The carrier of this invention overcomes many of the difficulties experienced heretofore. While it employs an outer container that is in some respects similar to convention open cartons, such container is expendable. That is, it is inexpensive and may be discarded without appreciable loss if it becomes damaged or unsightly after being used only a few times.

Requisite strength and rigidity are imparted to the carrier of this invention by a liner or sling that is removably disposed within the outer container in a manner that will be described, in detail, further along herein. The sling is preferably made of a relatively strong, waterproofed fibreboard and is provided with a reinforcing rod that is in the form of an open frame. The sling has its parts so constructed and arranged that it may be used by itself to carry a full load of bottles, if necessary. Also, the sling is collapsible and is compact when in collapsed condition, thereby facilitating handling and shipping of the same.

A preferred and recommended carrier constructed in accordance with this invention also includes a partition unit that is removably positioned within both the outer container and the sling. The partition unit comprises a plurality of upstanding and interlocking dividers that define a plurality of bottle-receiving compartments.

The outer container, sling and partition unit are made from blanks of suitable sheet material that may be readily cut, creased, folded and bent, as required. The outer container may be made of a relatively lightweight, inex-

2

pensive corrugated cardboard. The sling is preferably made of a heavy duty fibreboard, while the partition unit is made of a suitable grade and weight of fibreboard. Fibreboard is recommended for the sling and partition unit, to provide necessary strength and to permit repeated reuse of the same, with the initial or subsequent outer containers. Also, the sling and partition unit are treated to make them waterproof, thereby protecting them from moisture and prolonging their useful life. It will be understood that the term "paperboard," as used herein-after and in the appended claims, is intended to cover various sheet materials that may be used in the manufacture of the carrier of this invention, whether corrugated cardboard, fibreboard or other appropriate material.

The primary object of the invention is to provide a carrier for bottles or the like having improved features of construction.

Another object of the invention is to provide a bottle carrier having a relatively inexpensive disposable outer container.

Another object of the invention is to provide a bottle carrier having a relatively inexpensive outer container, which may be discarded when scuffed or otherwise rendered unsightly, and a relatively strong reinforced inner container, which may be reused a number of times with successive outer containers.

A further object of the invention is to provide a carrier of the character indicated, having its parts so constructed and arranged as to permit its being readily assembled or dismantled.

A still further object of the invention is to provide a bottle carrier that is simple and sturdy in construction, that is reasonable in cost, and that is capable of performing its intended functions in a satisfactory manner.

The enumerated objects, as well as additional objects, together with the advantages of the invention, will be readily understood by persons skilled in the art, upon reference to the following detailed description taken in conjunction with the accompanying drawings that respectively describe and illustrate a preferred embodiment of the invention.

In the drawings:

Fig. 1 is an isometric view of a complete carrier constructed in accordance with this invention;

Fig. 2 is an isometric view of the separate units of the carrier shown in Fig. 1, in the course of assembling the same;

Fig. 3 is a view similar to Fig. 1 and illustrating certain of the parts of the carrier in another relative position;

Fig. 4 is an isometric view of two units of the carrier shown in Fig. 1, prior to assembly; and

Fig. 5 is an enlarged fragmentary view, taken along line 5—5 of Fig. 1.

Referring now to the drawings wherein like reference characters denote corresponding parts throughout the several views, a preferred and recommended form of carrier embodying the invention is generally indicated by numeral 10 in Figs. 1 and 3 and consists of three nested units, namely, a first unit or outer container C, a second unit or sling S and a third unit or honeycomb partition P.

First unit or container C, best shown in Fig. 4, is made from a blank of a single piece of paperboard, such as a relatively lightweight, inexpensive corrugated cardboard. The blank is cut, creased and folded, and its parts are united to obtain a bottom wall 11, a pair of parallel side walls 12 and a pair of parallel end walls 13. One of the walls has an end flap 14 which bears against the inner surface of one of the end walls and is secured thereto by staples or the like 15, whereby the side and end walls are maintained in the illustrated upright positions.

Each side wall 12 has an extension 16 which is bent

and folded along crease lines 17 and 18 to obtain a narrow crimp 19 and a flap 20. As shown in Fig. 1, each crimp 19 projects inwardly and is generally parallel to bottom wall 11, while each flap 20 projects downwardly and is generally parallel to the corresponding side wall when the carrier is completely assembled.

Each end wall 13 is cut to form a hand opening 21 and a tab 22. Each side wall also has an extension 23 that is creased along lines 24 and 25 to define a corresponding narrow crimp 26 and a flap 27. The parts of extensions 23 are arranged similarly to those of extensions 16 in the assembled carrier (Fig. 1). That is, each narrow crimp 26 projects inwardly and is generally parallel to the bottom wall, while each flap 27 projects downwardly and is generally parallel to the corresponding end wall.

Extensions 16 and 23 are respectively narrower than side walls 12 and end walls 13 to permit proper disposition of the parts in the completed carton. Also, the junctures of the extensions and side and end walls define corner openings or notches 28. Formed in flaps 27 are hand openings 29 that align with hand openings 21.

Reference is next had to Figs. 4 and 5 for an understanding of the construction of the second unit or sling S. The sling is preferably made in part from a single rectangular piece of relatively heavy paperboard, such as an appropriate grade and weight of fibreboard that is treated to render the same waterproof. The piece of fibreboard is creased and folded along spaced parallel lines 30 to obtain a bottom wall 31 and a pair of end walls 32.

Each of the sling end walls is cut to form a hand opening 33. Integral with each end wall is an extension which is bent inwardly to provide a narrow arcuate top strip, as indicated at 34 in Fig. 5, and a flap 35, the latter bearing against and being secured to the corresponding end wall by staples or the like 36. Flaps 35 terminate in tongues 37. Arcuate top strips 34, and the immediately adjacent portions of end walls 32 and flaps 35, define a rod-receiving pocket 38 (Fig. 5).

The sling also includes a planar generally rectangular open frame 40 that is made from a continuous rod which is bent to provide a pair of parallel sides 41 and a pair of parallel ends 42. The opening defined by the frame corresponds generally in size and configuration to bottom wall 31. The junctures of sides 41 and ends 42 are bent to provide outwardly projecting frame corner portions 43 which register with notches 28 in the completed carrier. Frame sides 41 extend through pockets 38 and form pivot or hinge connections therewith. It will be apparent from an examination of Fig. 4 that the sling may be readily collapsed into a compact unit for purposes of storage or shipment and may subsequently be easily and quickly opened to the illustrated condition.

The illustrated form of the invention includes a third unit or partition P which consists of a first plurality of upstanding parallel dividers 44 and a second plurality of upstanding parallel dividers 45 that are normal to dividers 44. All dividers are made of a suitable paperboard. Dividers 44 are slotted upwardly from their bottom edges, while dividers 45 are slotted downwardly from their top edges, whereby to permit of interlocking engagement therebetween, as disclosed in greater detail in Verhoven Patent 1,976,530, dated October 9, 1934, to which reference may be had. The dividers are so constructed and arranged as to define a plurality of equal size bottle-receiving compartments 46. As is shown in Figs. 1 and 3, partition P divides the interior of the carrier into twelve such compartments.

In assembling the carrier, outer container C is placed on a support, such as a table or counter, with its bottom wall resting thereon and its flaps 20 and 27 projecting upwardly and outwardly, as shown in Fig. 4. The sling S is then inserted in the outer container so

that its bottom wall 31 bears against container bottom wall 11 and its end walls 32 bear against container end walls 13 (Fig. 2). Also, frame portion 43 will be in registry with notches 28 of the outer container. The flaps 20 and 27 are now swung downwardly over the top edges of the sling so that flaps 20 lie along container side walls 12 and flaps 27 lie along sling side walls 32. Tongues 37 are bent inwardly to project through hand openings 29, whereupon tabs 22 are bent so as to extend through aligned hand openings 33 and 29, as shown in Fig. 5. The illustrated arrangement of aligned hand openings, tongues and tabs provides a convenient and comfortable means for gripping the carrier and for properly distributing the load to the outer container and the sling.

The final step in assembling the carrier consists of inserting partition P in the nested outer container and sling. The partition, when in position, rests on the bottom wall of the sling and its ends bear against flaps 20 and 27, thereby maintaining these flaps in proper position. It will be observed from an examination of Fig. 1 that the partition terminates above the lower ends of flaps 20 and 27 but below the aligned hand openings. As a consequence, the partition does not interfere with the handling of a loaded carrier.

From the foregoing, it is believed that the construction, objects and advantages of my present invention will be readily comprehended by persons skilled in the art. It is to be clearly understood, however, that various changes in the carrier set forth above may be made without departing from the scope of the invention, it being intended that all matter contained in the description or shown in the drawings shall be interpreted as illustrative only and not in a limiting sense.

I claim:

1. A carrier for bottles and the like, comprising a hollow first unit made from a sheet of paperboard and comprising a bottom wall, a pair of spaced parallel side walls and a pair of spaced parallel end walls, each side and end wall of the first unit having an extension comprising a flap which is folded inwardly and downwardly and a second unit removably disposed within the first unit and including a bottom wall and a pair of spaced end walls, the bottom and end walls of said second unit being made from a sheet of paperboard substantially stronger, more durable and more water resistant than the paperboard from which the first unit is made, the bottom wall of said second unit being adjacent and generally parallel to the bottom wall of said first unit and the end walls of said second unit being disposed between an end wall and flap of said first unit, whereby said units fit snugly together, said second unit also including a frame comprising a rod defining an opening corresponding generally in size and configuration to the bottom wall of the second unit and including a pair of spaced parallel side portions and a pair of spaced parallel end portions, each end portion forming a hinge connection with the upper portion of an end wall of the second unit.

2. A carrier in accordance with claim 1 wherein each end wall and end wall flap of the first unit has a hand opening formed therein and each end wall of the second unit has a hand opening formed therein, each hand opening of the second unit being aligned with the corresponding hand openings in the adjacent end wall and end wall flap of the first unit.

3. In a carrier for bottles and the like, a hollow first unit made from a sheet of relatively inexpensive paperboard and comprising a bottom wall, a pair of spaced parallel side walls and a pair of spaced parallel end walls, each end wall having an extension comprising a flap which is folded inwardly and downwardly, each end wall and each end wall extension having a hand opening formed therein, and a second unit removably disposed within the first unit and including a bottom wall and a pair of spaced end walls, the last mentioned bottom and

end walls being made from a sheet of relatively expensive paperboard substantially stronger than the paperboard used for said first unit, whereby said second unit provides a major portion of the strength of said carrier, each end wall of said second unit being disposed between an end wall and flap of said first unit, being adjacent and generally parallel to corresponding walls of the first unit whereby said second unit fits snugly within said first unit, each end wall of the second unit having a hand opening formed therein and aligned with the hand openings in the adjacent end wall and flap of the first unit, said second unit also including a frame comprising a rod defining an opening corresponding generally in size and configuration to the bottom wall of the second unit and including a pair of spaced parallel side portions and a pair of spaced parallel end portions, each end portion forming a hinge connection with the upper portion of an end wall of the second unit.

4. In a carrier for bottles and the like, a hollow first unit made from a sheet of relatively inexpensive paperboard and comprising a bottom wall, a pair of spaced parallel side walls and a pair of spaced parallel end walls, each end wall having an extension comprising a flap which is folded inwardly and downwardly, each end wall and each end wall extension having a hand opening formed therein, and a second unit removably disposed within the first unit and including a bottom wall and a pair of spaced end walls, the last mentioned bottom and end walls being made from a sheet of relatively expensive paperboard stronger than the paperboard used for said first unit and being adjacent and generally parallel to corresponding walls of the first unit, each end wall of the second unit being disposed between an end wall and flap of said first unit and having a hand opening formed therein and aligned with the hand opening in the adjacent end wall and flap of the first unit, each end wall of said second unit having an extension comprising a flap which is folded inwardly and downwardly, each last mentioned flap terminating in a tongue which extends through the hand opening of the adjacent flap of the first unit, said second unit also including a frame comprising a rod defining an opening corresponding generally in size and configuration to the bottom wall of the second unit and including a pair of spaced parallel side portions and a pair of spaced parallel end portions, each end portion forming a hinge connection with the upper portion of an end wall of the second unit.

5. A carrier in accordance with claim 4, wherein each end wall of the first unit includes an integral tab that is hinged to the portion thereof which defines the upper edge of its hand opening, each tab extending through the hand openings of the adjacent end wall of the second unit and the corresponding flap.

6. In a carrier for bottles and the like, a hollow first unit made from a sheet of relatively inexpensive paperboard and comprising a bottom wall, a pair of spaced parallel side walls and a pair of spaced parallel end walls, each side and end wall of the first unit having an extension comprising a flap which is folded inwardly and downwardly, the junctures of said side and end walls and extensions of said first unit defining a notch in each upper corner of said first unit, each end wall having a hand opening formed therein, and a second unit removably disposed within the first unit and including a bottom wall and a pair of spaced end walls, the last mentioned bottom and end walls being made from a sheet of relatively expensive paperboard stronger than the paperboard used for said first unit and being adjacent and generally parallel to corresponding walls of the first unit, each end wall of the second unit having a hand opening formed therein and aligned with the hand opening in the adjacent end wall of the first unit, said second unit also including a frame comprising a rod defining an opening corresponding generally in size and configuration to the bottom wall

of the second unit and including a pair of spaced parallel side portions and a pair of spaced parallel end portions, each end portion forming a hinge connection with the upper portion of an end wall of the second unit, said rod including outwardly projecting bent portions formed at the junctures of its side and end portions, each bent portion of the rod registering with a corresponding notch in said first unit.

7. In a carrier for bottles and the like, a hollow first unit made from a sheet of relatively inexpensive paperboard and comprising a bottom wall, a pair of spaced parallel side walls and a pair of spaced parallel end walls, each end wall having a hand opening formed therein, a second unit removably disposed within the first unit and including a bottom wall and a pair of spaced end walls, the last mentioned bottom and end walls being made from a sheet of relatively expensive paperboard stronger than the paperboard used for said first unit and being adjacent and generally parallel to corresponding walls of the first unit, each end wall of the second unit having a hand opening formed therein and aligned with the hand opening in the adjacent end wall of the first unit, said second unit also including a frame comprising a rod defining an opening corresponding generally in size and configuration to the bottom wall of the second unit and including a pair of spaced parallel side portions and a pair of spaced parallel end portions, each end portion forming a hinge connection with the upper portion of an end wall of the second unit, said second unit providing the requisite structural strength for said carrier, and a third unit removably disposed in the second unit and comprising a plurality of interengaging upstanding dividers that define a plurality of bottle-receiving compartments, each end wall of the first unit having an extension comprising a flap which is folded inwardly and downwardly and having a hand opening aligned with the hand openings of corresponding end walls of both units, each end wall of the second unit being disposed between an end wall and flap of the first unit, each end wall of the first unit including an integral tab that is hinged to the portion thereof which defines the upper edge of its hand opening, each tab extending through the hand openings of the adjacent end wall of the second unit and the corresponding flap, each end wall of the second unit having an extension comprising a flap which is folded inwardly and downwardly, each last mentioned flap terminating in a tongue which extends through the hand opening of the adjacent flap of the first unit, said third unit bearing at opposite ends against the flaps of the first unit and terminating below the hand openings.
8. In a carrier for bottles and the like, a hollow first unit made from a sheet of relatively inexpensive paperboard and comprising a bottom wall, a pair of spaced parallel side walls and a pair of spaced parallel end walls, each end wall of said first unit having an extension comprising a flap which is folded inwardly and downwardly, each end wall and flap having a hand opening formed therein, and a second unit removably disposed within the first unit and including a bottom wall and a pair of spaced end walls, the last mentioned bottom and end walls being made from a sheet of relatively expensive paperboard substantially stronger, more durable and more water resistant than the paperboard used for said first unit and being adjacent and generally parallel to corresponding walls of the first unit, each end wall of the second unit having an extension comprising a flap which is folded inwardly and downwardly, the end walls and flaps of said second unit being disposed between the corresponding end walls and flaps of said first unit, each end wall of said second unit having a hand opening formed therein and aligned with the hand openings in the adjacent end wall and flap of the first unit, said second unit also including a frame comprising a rod defining an opening corresponding generally in size and configuration to the bottom wall of the second unit and including a pair of

spaced parallel side portions and a pair of spaced parallel end portions, each end portion forming a hinge connection with the upper portion of an end wall of the second unit.

9. In a carrier for bottles and the like, a hollow first unit made from a sheet of relatively inexpensive paperboard and comprising a bottom wall, a pair of spaced parallel side walls and a pair of spaced parallel end walls, each side and end wall of said first unit having an extension comprising a flap which is folded inwardly and downwardly, the junctures of said side and end walls and flaps of said first unit defining a notch in each upper corner of said first unit, each end walls having a hand opening formed therein, and a second unit removably disposed within the first unit and including a bottom wall and a pair of spaced end walls, the last mentioned bottom and end walls being made from a sheet of relatively expensive paperboard stronger than the paperboard used for said first unit and being adjacent and generally parallel to corresponding walls of the first unit, each end wall of the second unit having a hand opening formed therein and

aligned with the hand opening in the adjacent end wall of the first unit, said second unit also including a frame comprising a rod defining an opening corresponding generally in size and configuration to the bottom wall of the second unit and including a pair of spaced parallel side portions and a pair of spaced parallel end portions, each end portion forming a hinge connection with the upper portion of an end wall of the second unit, the junctures of the side and end portions of said rod forming corners which are disposed within said notches.
